Kevin Prince(57) **CLAIM**

I claim the ornamental design for a travel cup with lid, as shown and described.

DESCRIPTION

FIG. 1 is a perspective view of a travel cup with lid, showing my new design;

FIG. 2 is a front elevational view thereof;

FIG. 3 is a rear elevational view thereof;

FIG. 4 is a left-side elevational view thereof, the right-side elevational view being a mirror image thereof;

FIG. 5 is a top plan view thereof; and,

FIG. 6 is a bottom plan view thereof.

The broken lines showing text in FIGS. 1, 3 and 5 depict environmental matter and form no part of the claimed design. The broken lines in FIG. 6 illustrate portions of the travel cup with lid that forms no part of the claimed design.
